CLAIM

The ornamental design for an illuminated zipper pendant, as shown and described.

DESCRIPTION

FIG. 1 is a front perspective view of an illuminated zipper pendant illustrating my new design;

FIG. 2 is a back view of the design of FIG. 1;

FIG. 3 is a front view of the design of FIG. 1;

FIG. 4 is a side view of the design of FIG. 1;

FIG. 5 is a side view of the design of FIG. 1;

FIG. 6 is a top view of the design of FIG. 1;

FIG. 7 is a bottom view of the design of FIG. 1; and,

FIG. 8 is another perspective view of the design of FIG. 1 shown in a state of use.

The broken lines in the drawings represent portions of the illuminated zipper pendant and form no part of the claimed design. The broken lines in FIGS. 1 and 8 showing a cord and human figure represent environmental subject matter only and form no part of the claimed design. The dash-dot-dash lines radiating from the illuminated zipper pendant in FIG. 8 indicate illumination only and form no part of the claimed design.
